UNITED STATES PATENT OFFICE.

HENRY FLETTTER, OF KALAMAZOO, MICHIGAN, ASSIGNOR OF ONE-HALF TO
DAVID LILIENFELD, OF SAME PLACE.

NUT-LOCK.

SPECIFICATION forming part of Letters Patent No. 277,474, dated May 15, 1883.

Application filed November 4, 1882. (No model.)

To all whom it may concern:

Be it known that I, HENRY FLETTTER, a citizen of the United States, residing at Kalamazoo, county of Kalamazoo, State of Michigan, 5 have invented a new and useful Nut-Lock, of which the following is a specification.

My invention has for its object an improved construction and combination of parts for locking nuts.

10 The general construction consists in a base plate or washer having an extension-center corresponding in size with the nut, and forming a base for said nut to rest against, a locking-band located around said extension-center and the portion of the nut engaging it, and a key located in open recesses in the nut and over the locking-band to hold said band in place.

15 In the drawings forming a part of this specification, Figure 1 is a top view; Fig. 2, side elevation; Fig. 3, base-plate; Fig. 4, locking-band; Fig. 5, the key; and Fig. 6 a perspective view with the locking-band and key detached.

20 D is a nut having open recesses c c at opposite corners in the side of the nut next to the center extension, B', of the base-plate B. This base-plate B may be secured to the timber or metal through which the bolt P is located by screws, as in Figs. 1 and 6, or by other means; or when used as a washer lugs v may be formed on its side, Figs. 2 and 3, and located in mortises adapted to receive them. The locking-band a is made a little higher than 25 the thickness or height of the center extension, B', Fig. 2. In the operation, the nut D, having been screwed onto bolt P and resting against center extension, B', as in Fig. 6, the

locking-band a is placed around said nut and center extension, Fig. 2, and the key r inserted 40 over the locking-band and in recesses c c, as in Fig. 1. By means of the recesses c c being open, should the key r become so rusted in as to be difficult to be removed, said key may be readily opened by bending the arms laterally 45 out of said recess, and a new key may be employed for future use.

If desired, in lieu of key r, for holding the locking-band a in place, spring-studs S S may be employed, said locking-band being pressed between said studs and the nut and its base-plate, as in Fig. 2.

Having thus described my invention, what I claim as new, and desire to secure by Letters Patent, is—

55 1. The base-plate having a perforated center extension corresponding with the size of the nut used, in combination with a nut having the open key-recesses, and the locking-band and key, all substantially as described and 60 shown.

2. A nut resting on a base extension corresponding with it in size, in combination with a locking-band, and means for holding said band in place, to effect the objects set forth, 65 substantially as described.

3. A perforated base plate or washer provided with a center extension, and means to prevent it from turning, in combination with a nut having the corner recesses, a locking-band, and means for holding said band in place, substantially as set forth.

HENRY FLETTTER.

Witnesses:

DAVID LILIENFELD,
J. BEROLZHEIMER.
